TELEVISION SYSTEM

Vladimir K. Zworykin, Haddonfield, and Gregory N. Ogleblinsky, Collingswood, N. J., assignors to Radio Corporation of America, a corporation of Delaware

Application March 10, 1932, Serial No. 597,898

5 Claims. (Cl. 178—7.2)

Our invention relates to television systems, and more particularly to systems of the type including an electron tube for developing picture signals.

8 In using television transmission tubes of the general type disclosed in Patent No. 1,773,980 of August 26, 1930, to Philo T. Farnsworth, an image of the object is projected onto a cathode plate coated with light-sensitive material. A 10 beam of electrons is thereby developed, in which the electrons move with considerable velocity from the cathode plate to an anode plate having a central aperture back of which an anode element is supported. The degree of electron 15 emission at any instant from a particular elemental area of the cathode plate is dependent directly upon the light intensity at that instant on this elemental area. For the purpose of preventing dispersion of the electrons in their 20 travel from the cathode plate to the anode plate, a focusing coil is disposed about the tube and operates to develop a magnetic focusing field having lines of force extending in a direction generally axially of the tube.

25 Scanning is accomplished by so deflecting the entire electron beam both horizontally and vertically that the electrons from the elemental areas, in a transverse section of the beam at the anode plate, pass successively through the central aperture to the anode element referred to. Picture signals are thereby developed and supplied to suitable apparatus for transmission.

It has been found expedient to deflect the beam electromagnetically, for which purpose horizontal 35 and vertical deflection coils are used to develop deflecting fields transverse to the focusing field. The advantages of the combination of electromagnetic focusing and electromagnetic deflection, however, have heretofore been offset by several disadvantages. In the first place, the deflection of the beam, instead of being at right angles to the transverse electromagnetic deflecting fields, is at an oblique angle, the angular difference depending upon the relation between 40 the intensities of the focusing and deflecting fields. In the second place, the focusing is appreciably distorted under the influence of the deflecting fields, the degree of distortion increasing with increase in the deflection and being dependent upon the relative intensities of the focusing and deflecting fields.

With the foregoing in mind, it is one of the objects of our invention to provide an improved television system of the character referred to 55 wherein the beam is both focused and deflected

electromagnetically without appreciable distortion of the focusing or the deflecting angle.

Other objects and advantages will hereinafter appear.

For the purpose of illustrating our invention, 5 an embodiment thereof is shown in the drawing, wherein

Figure 1 is a diagrammatic view of a television transmission system embodying our invention; 10 and

Figs. 2 and 3 are diagrammatic views illustrating several modifications.

With reference to Fig. 1, the reference numeral 10 designates an electron tube of the general type disclosed in the patent referred to, and which is effective to develop picture signals for transmission. Such a tube comprises a photosensitive cathode 12, upon which is projected an image of an object 14 being televised, the latter being 15 illuminated by a suitable light source 16. In operation, electrons are emitted from the cathode 12 and move at high velocity in the form of a beam 18 directed at an anode plate 20 which is maintained at a high positive potential with respect to the cathode by a battery 22 or other potential 20 source.

The anode plate is provided at the center thereof with a small aperture 24, back of which is supported an anode element 26 connected as shown to one end of a resistance 28.

For the purpose of focusing the beam 18 on the plate 20, an electromagnetic coil 30, supplied by a battery 32, is so disposed as shown about the tube, that the flux lines extend substantially parallel to the tube axis. The strength of the focusing electromagnetic field is so adjusted by a resistance 34 that the electrons emitted from any elemental area of the cathode 12, such as the area 36, normally come to a focus on the anode plate 20. That is, the electrons emitted from the elemental area 36, for example, travel at high velocity along paths generally axially of the tube, and under the influence of the focusing electromagnetic field come to a focus at the opposite, corresponding elemental area 38 of the anode plate 20. The degree of electron emission at the instant from the photosensitive area 36 is a direct function of the light intensity on this area at this instant. In like manner, there is electron emission from each of the elemental areas of the cathode 12, the degree of emission depending directly upon the light intensity on the particular area at the instant. The focusing electromagnetic field is effective to focus the electrons 45

50

55

emitted from any elemental area on the anode plate 20.

Scanning is accomplished by so deflecting the entire beam 18 transversely in both horizontal and vertical directions that during each picture-frame period the electrons at the individual elemental regions in a cross-section of the beam, taken at the anode plate 20, pass successively through the aperture 24 and strike the anode element 26. This action is effective to develop picture signals in the resistance 28, and these are amplified and transmitted in the well known manner by a suitable amplifier and radio transmitter 40.

For the purpose of deflecting the beam 18 in the manner aforesaid, electromagnetic coils 42 and 44 operate to develop electromagnetic fields wherein the flux lines are transverse to the tube axis. The coils 42 are connected to the output of a suitable generator 46 which causes, for example, a saw-tooth current wave at five thousand cycles to pass through these coils, the resulting field operating to deflect the beam 18 five thousand times a second, horizontally. The coils 44 are connected to the output of a suitable generator 48 which causes, for example, a saw-tooth current wave at ten cycles to pass through these coils, the resulting field operating to deflect the beam 18 ten times a second, vertically.

The combination of electromagnetic focusing and electromagnetic deflection of the beam 18 has well known advantages. There is, however, a serious disadvantage which will now be explained, for which purpose consideration will be given to the electrons emitted from one of the individual elemental areas of the cathode 12, such as the area 36. As the beam 18 is deflected, and when the ray 19 of electrons issuing from the elemental area 36 is in the position indicated by dash lines, whereat this ray is directed at the aperture 24, the electrons are focused at the point 50, an appreciable distance in front of this aperture. This causes the electrons from the particular area 36 to be out of focus in some degree with respect to the anode element 26.

The various rays of electrons, propagated from elemental areas on the cathode 12 further removed from the center thereof than the area 36, will be out of focus a greater degree with respect to the anode element 26, during the scanning action. The result of this action is that the transmitted picture has substantially less degree of detail around the outside portion than at the central portion. The degree of focusing on the aperture 24 may be made more uniform over the entire picture area by causing the beam to be focused normally on a plane slightly to the right of the anode plate 20, so that when the various electron rays are deflected to be directed at the aperture 24, they are more nearly at a focus with respect to the anode element 26. This expedient, however, is a compromise, and does not provide for the best operating action in the way of picture detail.

For the purpose of avoiding the difficulty outlined above, we propose to superimpose upon the electromagnetic focusing field a corrective wave form whereby the point at which the electrons in any ray come to a focus is varied as the beam 18 is deflected, the resulting action being that when any ray is deflected to the position whereat it is directed at the aperture 24, the electrons meet at a focus on the anode element 26. For this purpose, a resistance 52 and a condenser 54 are connected as shown to the output of the

generator 46, and operate to integrate the wave form of the output from this generator to develop the wave form necessary for the correction referred to. The corrective wave form is superimposed upon the normal focusing field by an auxiliary electromagnetic coil 56 which is connected to the resistance-condenser combination 52, 54 through a suitable coupling tube 58. The focusing field is thereby varied in a manner dependent upon the characteristic wave-shape of the electromagnetic field for horizontal deflection of the beam 18.

In like manner, another corrective wave form is superimposed upon the normal focusing field by means of a resistance 60 and a condenser 62 connected as shown to the output of the generator 48. For this purpose, a second auxiliary electromagnetic coil 64 is disposed about the tube 10 and is connected to the resistance-condenser combination 60, 62 by a suitable coupling tube 66. The focusing field is thereby varied in a manner dependent upon the characteristic wave-shape of the electromagnetic field for vertical deflection of the beam 18.

In operation, the corrective wave forms operate automatically to vary the focusing field in a manner similar to the characteristic wave-shapes of the horizontal and vertical deflecting fields so that, at any instant during the scanning action, the electrons are focused on the aperture 24 and the anode element 26 immediately back of the same. The corrective electrical waves in the coils 56 and 64 can be said to approximate in shape the integrals of the respective wave-shapes developed by the generators 46 and 48.

In systems wherein scanning is accomplished by passing sine waves through the deflecting coils 42 and 44, modification is made as shown in Fig. 2. In this case, the generator 68 develops a sine wave at five thousand cycles, and the integral of this wave is obtained, as an approximation, by doubling the frequency by means of a suitable frequency doubler 70. It is proposed to use a suitable phase shifter 72 to compensate for a possible discrepancy in phase incident to the use of the frequency doubler 70. The auxiliary coil 56 is connected to the output of the phase shifter 72 through a suitable coupling tube 74.

The corrective wave form is developed and supplied to the auxiliary coil 64 by a similar combination comprising a generator 76 for developing a sine wave at ten cycles, a frequency doubler 78, a phase shifter 80, and a suitable coupling tube 82.

As in Fig. 1, the corrective electrical waves in the coils 56 and 64 can be said to approximate in shape the integrals of the respective wave-shapes developed by the generators 68 and 76.

The operating action in the system shown in Fig. 2 is the same as that described in connection with Fig. 1. That is, corrective wave forms are superimposed upon the normal focusing field and operate to vary the focusing in such manner that, at any instant during the scanning action, the electrons are focused on the aperture 24 and the anode element 26.

In lieu of using independent auxiliary coils 56 and 64, the corrective wave forms may be superimposed on the normal focusing field by induction, as shown in Fig. 3. In such case, suitable transformers 84 and 86 are connected as shown between the coupling tubes and the exciting circuit for the focusing coil 30.

We claim as our invention:

1. In electron apparatus of the character described, anode structure provided with an aperture, an anode element supported on one side of said structure and in proximity to said aperture, photosensitive cathode structure supported on the other side of said anode structure and in spaced relation with respect thereto, means for focusing an image on said cathode structure to develop a beam of electron rays directed at said anode structure, means for focusing said beam on said anode structure, means for deflecting said beam in scanning fashion with respect to said aperture, and means controlled by said deflecting means and operating to vary the point of focus of the individual rays to a point substantially at said aperture. 5
2. The combination with electron apparatus of the character described comprising a tube, electrodes supported in said tube in spaced relation with respect to each other, said apparatus being characterized by the fact that in operation a beam of electrons is developed at one of said electrodes and is directed at the other electrode, 10 means for deflecting the electrons, and an electromagnetic coil disposed about said tube and co-axially therewith for developing an electromagnetic field; of an auxiliary electromagnetic coil disposed about said tube and co-axially therewith for developing an electromagnetic field superimposed upon said first-named field, and means controlled by said deflecting means and operating to cause an electrical wave to pass through said auxiliary coil. 15
3. The combination with electron apparatus of the character described comprising a tube, electrodes supported in said tube in spaced relation with respect to each other, said apparatus being characterized by the fact that in operation a beam of electrons is developed at one of said electrodes and is directed at the other electrode, means for deflecting the electrons, and an electromagnetic coil disposed about said tube and co-axially therewith for developing an electro- 20
- magnetic field for focusing the beam of electrons with respect to said other electrode; of means controlled by said deflecting means and operating to develop a second electromagnetic field superimposed upon the focusing field. 25
4. The combination with electron apparatus of the character described comprising a tube, electrodes supported in said tube in spaced relation with respect to each other, said apparatus being characterized by the fact that in operation a beam of electrons is developed at one of said electrodes and is directed at the other electrode, electromagnetic means for focusing said beam with respect to said other electrode, and electromagnetic means for deflecting said beam in scanning 30
- fashion with respect to said other electrode; of means controlled by said deflecting means and operating in turn to control the focusing action of said first-named electromagnetic means in such manner that during deflection the focus of the electrons at a fixed elemental zone at said other electrode is maintained. 35
5. The combination with electron apparatus of the character described comprising a tube, electrodes supported in said tube in spaced relation with respect to each other, said apparatus being characterized by the fact that in operation a beam of electrons is developed at one of said electrodes and is directed at the other electrode, means for developing an electromagnetic field 40
- for focusing said beam on said other electrode, means for developing an electromagnetic field for deflecting said beam horizontally, and means for developing an electromagnetic field for deflecting said beam vertically; of means for superimposing on the focusing field a wave form dependent upon the characteristic wave form of the horizontal deflecting field, and means for superimposing on the focusing field a wave form dependent upon the characteristic wave form of the vertical deflecting field. 45
